(57) **CLAIM**

The ornamental design for a combined speaker and light as
shown and described.

DESCRIPTION

FIG. 1 is a perspective view of a combined speaker and light in accordance with a first embodiment of my new design; FIG. 2 is a front elevation view of the combined speaker and light of FIG. 1;

FIG. 3 is a rear elevation view of the combined speaker and light of FIG. 1;

FIG. 4 is a front elevation view with the lattice work removed to show the structure of the light of the combined speaker and light of FIG. 1;

FIG. 5 is a rear elevation view with the lattice work removed to show the structure of the light of the combined speaker and light of FIG. 1;

FIG. 6 is right side elevation view of the combined speaker and light of FIG. 1;

FIG. 7 is a left side elevation view of the combined speaker and light of FIG. 1;

FIG. 8 is a top plan view of the combined speaker and light of FIG. 1;

FIG. 9 is a bottom plan view of the combined speaker and light of FIG. 1;

FIG. 10 is a perspective view of a combined speaker and light in accordance with a second embodiment of my new design;

FIG. 11 is a front elevation view of the combined speaker and light of FIG. 10;

FIG. 12 is a rear elevation view of the combined speaker and light of FIG. 10;

FIG. 13 is a front elevation view with the lattice work removed to show the structure of the light of the combined speaker and light of FIG. 10;

FIG. 14 is a rear elevation view with the lattice work removed to show the structure of the light of the combined speaker and light of FIG. 10;

FIG. 15 is right side elevation view of the combined speaker and light of FIG. 10;

FIG. 16 is a left side elevation view of the combined speaker and light of FIG. 10;

FIG. 17 is a top plan view of the combined speaker and light of FIG. 10;

FIG. 18 is a bottom plan view of the combined speaker and light of FIG. 10;

(Continued)

FIG. 19 is a perspective view of a combined speaker and light in accordance with a third embodiment of my new design;

FIG. 20 is a front elevation view of the combined speaker and light of FIG. 19;

FIG. 21 is a rear elevation view of the combined speaker and light of FIG. 19;

FIG. 22 is a front elevation view with the lattice work removed to show the structure of the light of the combined speaker and light of FIG. 19;

FIG. 23 is a rear elevation view with the lattice work removed to show the structure of the light of the combined speaker and light of FIG. 19;

FIG. 24 is right side elevation view of the combined speaker and light of FIG. 19;

FIG. 25 is a left side elevation view of the combined speaker and light of FIG. 19;

FIG. 26 is a top plan view of the combined speaker and light of FIG. 19; and,

FIG. 27 is a bottom plan view of the combined speaker and light of FIG. 19.
